UNITED STATES PATENT OFFICE.

FREDERICK L. ROBINSON AND JOHN McCABE, OF CHEYENNE, WYOMING.

TRACK-SANDING APPARATUS.

No. 844,618.

Specification of Letters Patent.

Patented Feb. 19, 1907.

Application filed September 15, 1906. Serial No. 334,756.

To all whom it may concern:

Be it known that we, FREDERICK L. ROBINSON and JOHN McCABE, citizens of the United States, residing at Cheyenne, in the county of Laramie and State of Wyoming, have invented a new and useful Track-Sanding Apparatus, of which the following is a specification.

This invention relates to means carried by locomotives or traction-cars for delivering sand to the tracks whenever deemed desirable to prevent slipping of the wheels.

The principal object is to provide simple mechanism of a novel nature which will insure the delivery of sand, is readily adjustable to secure the proper flow of the material, is not apt to become clogged or inoperative, but may be made to clean itself, and yet is so constructed that the interior parts are readily accessible whenever it becomes necessary to examine or repair the same.

The preferred form of construction is illustrated in the accompanying drawings, wherein—

Figure 1 is a side elevation of a portion of a locomotive, showing the novel sanding mechanism applied thereto. Fig. 2 is an end elevation of a portion thereof, shown on an enlarged scale. Fig. 3 is a side elevation of the same. Fig. 4 is a top plan view. Fig. 5 is a sectional view on the line 5-5 of Fig. 4. Fig. 6 is a sectional view on the line 6-6 of Fig. 4.

Similar reference-numerals designate corresponding parts in all the figures of the drawings.

While the invention in the present case is shown in connection with a locomotive, it is to be understood that it is not limited thereto, but is capable of successful use upon cars of any character having a motive-fluid supply.

In the present embodiment the sand-box of the locomotive is designated 7, and leading therefrom is a pipe 8, connected to the upper end of a casing 9. This casing 9 is divided into spaced depending legs 10, each having oppositely-extending nipples 11 and 12. The lower ends of the legs are closed by detachable plugs 13, threaded therewith. Sand-conducting pipes 14 extend from the nipples 11 and have their discharge ends 15 arranged, respectively, in front and in rear of the driving-wheels of the locomotive.

Plugs 16 are threaded into the nipples 12, and screwed into the inner ends of these

plugs are nozzles 17, that project across the legs toward the nipples 11, terminating short of the same. Lock-nuts 18 are threaded upon the exterior portions of the plugs and are arranged to jam against the outer end of the nipples 12. Motive-fluid-conducting pipes 19, connected with any suitable source of supply through the medium of a common pipe 20, have valves 21, located at their juncture with the pipe 20. The other ends of these pipes are connected by bonnet-nuts 22 to couplings 23, that are threaded into the outer ends of the plugs 16. Thus motive fluid is supplied to the nozzles 17. The volume of the flow is controlled, however, by turning valves or plugs 24, that are journaled in the couplings 23, and have angularly-disposed passage-ways 25 and 26 therethrough, said passage-ways being of different diameters. The upper ends of the valves are provided with crossed notches 27 and 28 of different sizes to correspond to the passage-ways, and thus constitute indicators therefor.

Under ordinary conditions the smaller passage-ways 26 are in line with the bores through the motive-fluid-supply conduit, and consequently the larger passage-ways are cut out. If, therefore, motive fluid is admitted to either of the conduits 19, it will be projected through the nozzle 17, connected to such conduit, and the sand located within the casing will be expelled therefrom through the delivery-pipe 14. Should the passage-way 25 become clogged by the accumulation of sand therein under ordinary conditions, if the valve is reversed or given a half-turn the passage-way will be cleaned automatically, for the former discharge end thereof will then become the inlet end. If, however, this will not effect the desired cleansing action, a quarter-turn of the valve will bring the larger passage-way into line with the bore through the nipple, and a greater volume of air can then flow through the nozzle. Thus two different pressures can be secured, and, moreover, the nozzle can be readily adjusted toward and from the inlet end of the sand-conducting pipe 14 by screwing the plug 16 into or out of the casing, being readily held by the jam-nut 18. If at any time it becomes desirable or necessary to gain access to the interior of the casing, it is only necessary to remove either or both of the plugs 13.

From the foregoing it is thought that the construction, operation, and many advan-

5 tages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described our invention, what we claim as new, and desire to secure by Letters Patent, is—

1. In sanding apparatus of the character set forth, the combination with a casing having an upper sand-inlet and an offset sand-discharge, of a motive-fluid conduit, a coupling directly connecting the conduit and casing on the side opposite the sand-discharge, and a reversible controlling-valve located in the coupling directly adjacent to the casing, said valve having a fluid-conducting passage-way therethrough, either end of which may be made the inlet of said passage-way by reversing the valve.

2. In sanding apparatus of the character set forth, the combination with a sand-conduit, of motive-fluid-conducting means, connections between the conducting means and conduit, including a coupling having an inlet and an outlet, a rotatable controlling-valve located in the conduit and having passage-ways of different diameters therethrough that are movable into alignment with the inlet and outlet of the coupling, both ends of each passage-way being movable into association with said inlet of the coupling to secure the passage of the motive fluid in opposite directions through each passage-way.

3. In a sanding apparatus of the character set forth, the combination with a sand-conduit, of motive-fluid-conducting means, connections between the conducting means and conduit, including a coupling having an inlet and an outlet, a rotatable controlling-valve located in the conduit and having angularly-disposed passage-ways of different diameters therethrough that are movable into alignment with the inlet and outlet of the coupling, both ends of each passage-way being movable into association with said inlet of the coupling to secure the passage of the motive fluid in opposite directions through each passage-way.

4. In sanding apparatus of the character set forth, the combination with a casing having a sand-outlet, and a sand-inlet, of a motive-fluid-conducting conduit connected to the casing and having a nozzle co-operating with the sand-outlet, and a rotatable plug

journalized in the motive-fluid conduit contiguous to its junction with the casing, said 60 plug having angularly-disposed intersecting passage-ways of different diameters therethrough, either of which may be brought into alignment with the bore of the conduit to permit the flow of different volumes of 65 motive fluid through said nozzle, and both ends of each passage-way being movable to a position to constitute the inlet of such passage-way in order to secure the passage of motive fluid in opposite directions through 70 each passage-way.

5. In sanding apparatus of the character set forth, the combination with a casing having an upper sand-inlet, and an offset sand-discharge, of a plug threaded into the casing 75 from the outside and disposed in the opposite side thereof to the discharge, a nozzle carried by the inner end of the plug and projecting toward the outlet, a supply-conduit, a coupling connecting the conduit and the 80 outer end of the plug, and a controlling-valve located in the coupling.

6. In sanding apparatus of the character set forth, the combination with a casing having an upper sand-inlet, and an offset sand-discharge, of a plug threaded into the casing, 85 a nozzle carried by the plug and projecting toward the sand-discharge, a lock-nut threaded on the plug and bearing against the casing, a motive-fluid-conducting pipe, a coupling connecting the pipe and the plug, and a rotatable valve journalized in the coupling 90 and having angularly-disposed openings of different diameters therethrough.

7. In sanding apparatus of the character set forth, the combination with a casing having an upper inlet, and depending legs, of 95 plugs detachably fitted into the lower ends of the legs, said legs furthermore having aligned oppositely-projecting nipples, sand-conducting pipes connected to certain of the nipples, nozzles connected to the other nipples, and extending into the legs toward the sand-conducting pipes, motive-fluid-conducting means, couplings disposed exteriorly of the 100 legs and connecting said conducting means and the nozzles, and controlling-valves located in said couplings.

In testimony that we claim the foregoing as our own we have hereto affixed our signatures in the presence of two witnesses.

FREDERICK L. ROBINSON.
JOHN McCABE.
